Application May 18, 1932, Serial No. 612,144

7 Claims. (Cl. 250—27.5)

This invention relates to fluid circulation systems and more particularly to cooling jackets for high power electron discharge devices of the external anode type.

5 In high power electron discharge devices, the anode is heated to high temperatures during the operation of the device and it becomes necessary to convey the heat away from the anode to prevent distortion and destruction thereof. The 10 cooling of the anode is usually accomplished by passing a cooling medium such as water over the outer surface of the anode, for example, through a jacket consisting of the anode and a surrounding casing mounted thereupon. Heretofore, it 15 has been the customary practice to provide an inlet at one end of the jacket and an outlet at the other end of the jacket and to provide a relatively large and uniform clearance between the anode and the surrounding casing. This 20 construction has been found satisfactory for devices of a rating of a few kilowatts.

However, in jackets of such construction, the cooling medium is caused to swirl about the anode and as a result eddies are formed in the 25 medium which impede the flow of the cooling medium and produce air pockets within the chamber adjacent the anode surface. Moreover, because of the swirling action and the resultant 30 centrifugal forces, the cooling medium tends to flow away from the anode and toward the inner wall of the surrounding casing. Consequently the heat from the anode is dissipated inefficiently and in devices having a relatively high capacity, for example 100 kilowatts, the anode is not 35 adequately cooled.

An object of this invention is to efficiently and effectively cool anodes in high power electron discharge devices.

In accordance with a feature of this invention 40 the above described difficulties are overcome by so constructing the jacket that the cooling medium flows parallel to the longitudinal axis of the anode and in substantially uniform contact with the entire surface of the anode.

45 In a specific embodiment of this invention an electron discharge device comprises an enclosing vessel including a cylindrical metallic portion which serves as the anode of the device. A metallic casing encircles the anode and consists of two similar opposed sections each including a cylindrical portion and an annular tubular end portion. The cylindrical portions are suitably joined together to form a cylindrical shell concentrically disposed about the anode. The 50 inner diameter of the shell is but slightly great-

er than the outer diameter of the anode so that a very narrow passageway is formed. The end portions of the casing are brazed to the anode and are so formed as to be flexible to allow expansion and contraction of the anode. Each 5 end portion is provided with a plurality of opposed tubular extensions disposed with their axes substantially perpendicular to the longitudinal axis of the anode. The extensions on one end portion constitute inlets for the jacket while the extensions on the other end portion constitute outlets. The aggregate cross-sectional area of the inlets, and of the outlets is made equal to the area of the passageway between the anode and the encircling cylindrical casing, so that a 10 constant velocity of flow is maintained through the cooling jacket.

As a cooling medium such as water enters the 15 inlets, the tubular end portion communicating with the inlets becomes substantially filled with the medium, swirling action being prevented by the opposed disposition of the inlets. The medium then flows into the passageway between the anode and the encircling cylindrical casing, 20 passes over the anode surface parallel to the 25 longitudinal axis of the latter and flows out through the outlets.

This construction prevents the formation of 30 air pockets within the jacket and insures good contact of the cooling medium with the anode so that the heat of the anode is dissipated effectively and efficiently. Electrolytic action in the joints of the jacket occasioned by the high 35 anode potentials employed in the operation of the device is substantially eliminated and leaks in the jacket are prevented. Rupture of the 40 joints is prevented by expansion of the end portions which compensate for unequal expansion between the anode and the casing and thereby minimize the stresses in the joints between the anode and the casing.

The invention will be understood more clearly 45 from the following detailed description with reference to the accompanying drawing in which:

Fig. 1 is a perspective view in elevation of a 50 high power electron discharge device embodying a cooling jacket of this invention, and a mounting therefor;

Fig. 2 is an enlarged cross-sectional view of 55 the cooling jacket and the anode of the device illustrating the space relationship of these elements and showing the configuration of the end portions of the jacket;

Fig. 3 is an enlarged end view, partly in cross-section, of the cooling jacket; and

Fig. 4 is an enlarged exploded view of the coupling and the support between the cooling jacket and the frame shown in Fig. 1.

Referring now to the drawing, a specific embodiment of this invention includes a high power electron discharge device comprising an enclosing vessel having a cylindrical metallic portion 10, preferably of copper, which is adapted to serve as the anode of the device, and vitreous end portions 11 and 12, each hermetically sealed to the metallic portion 10 in accordance with the method disclosed in William G. Houskeeper Patent 1,294,466, granted February 18, 1919. The vitreous portions 11 and 12 are provided with re-entrant stems 13 and 14, respectively. A cathode assembly and grid or control electrode structure (not shown) are supported from the stems 13 and 14, respectively, as shown and described more fully in a copending application of Victor L. Ronci and James E. Clark, Serial No. 612,143, filed May 18, 1932. The grid or control electrode may be connected to an external circuit by a conductor 15 which is secured to a metallic band 16 clamped about a metallic cap 17 extending from the stem 14. Leading-in conductors 18 for the cathode, are clamped to a band 19 encircling the end portion 11, and are insulated from the band by tubular insulators 20. During transportation and mounting of the device, the free ends of the conductors 18 may be clamped in sockets 21 mounted on the band 19.

During the operation of the device the anode is heated to high temperatures and it becomes necessary, therefore, to dissipate the heat of the anode to prevent buckling or rupture thereof. For this purpose a jacket is provided around the anode through which a cooling medium, such as water, may be circulated in contact with the outer surface of the anode. As shown more clearly in Fig. 2, the jacket, which may be of a drawn non-ferrous material, comprises a pair of similar sections including overlapping cylindrical shells 22 and 23 which are joined, as at 24, preferably by brazing, and form a cylindrical casing concentrically disposed about the anode 10. The clearance between the anode 10 and cylindrical wall of the shells 22 and 23 is preferably relatively small, for example of the order of 5/32" to form a narrow annular channel or passageway. One of the sections of the jacket is formed with an integral hollow toroidal end portion 25 having diametrically opposed tubular extensions 26 which form inlets for the jacket. The other section is provided with a similar integral hollow toroidal end portion 27 having diametrically opposed tubular extensions 28 which form outlets for the jacket. The cross-sectional area of the opening in each of the inlets 26 and outlets 28 is preferably equal to one half the cross-sectional tubular area of the passageway between the anode 10 and shells 22 and 23 to insure a uniform velocity of flow through the jacket. The passageways in the toroidal portions 25 and 27 are preferably much greater in cross-sectional area than the cross-sectional area of the passageway between the shells 22 and 23 and the anode 10, and are connected to the latter passageway by reduced annular openings or channels 29 and 30, respectively. The end portions 25 and 27 are joined to the anode 10 as at 31 and 32, respectively, preferably by brazing, to prevent any electrolytic action at the joint and to form a fluid-tight seal.

A cooling medium, such as water, is caused to flow under pressure into the inlets 26 and sub-

stantially fills the end portion 25. Since the inlets 26 are diametrically opposed the pressures of the streams passing through the inlets are counter-balanced and neutralized so that swirling of the medium is prevented and a uniform pressure head is provided at the annular opening or channel 29. After the end portion 25 is filled, the cooling medium flows through the annular opening or channel 29 and into the passageway between the anode 10 and the cylindrical shells 22 and 23. Since a uniform pressure head is maintained at the opening or channel 29, the cooling medium will flow over the surface of the anode 10 parallel to the longitudinal axis of the anode without swirling action or eddy currents. The small clearance between the anode and the surrounding casing, together with the relatively high and uniform pressure insured by the narrow opening or channel 29, prevents the formation of air pockets adjacent the anode and results in a high velocity of flow so that uniform and efficient contact is obtained between the cooling medium and all parts of the anode surface between the openings 29 and 30. After passing over the outer surface of the anode 10, the cooling medium flows out through the opening or channel 30 and the outlets 28. The narrow opening or channel 30 partially retards the flow of the cooling medium and thereby prevents the formation of air pockets adjacent that part of the anode near the end portion 27 of the jacket.

During the operation of the device, both the anode 10 and the surrounding casing expand and contract with temperature variations, and due to the different materials of the anode and the casing and the difference in the temperatures to which the anode and casing are heated, the expansion and contraction are not uniform. The depressed wall of the toroidal end portions 25 and 27 act as expansion members and compensate for the unequal variations in the anode and casing so that the setting up of deleterious stresses in the joints between the anode and the end portions of the casing is prevented.

The electron discharge device may be mounted as shown in Fig. 1, upon a frame which comprises channel beam uprights 33 and channel cross-beams 34 secured together by bolts 35. Another frame including rigid bars 36 and 37 is supported from the cross-beams 34 by insulators 38. The frames and insulators are secured together by bolts and nuts which extend through the insulators 38 and are insulated from the beams 34 and bars 36. A plurality of brackets 43 are mounted upon the bars 36, by bolts 44, and are formed with semi-circular hanger or bearing portions 45. An interiorly threaded coupler 46 having spaced circumferential flanges 47 and a nut portion 48, is held in the hanger or bearing 45 by a clamping bracket 49, which is secured to the hanger 45, together with the spacers 50, by screws 51. A nipple including a threaded portion 52 extends into the coupler 46, and a reduced end portion 53 of the nipple is threaded into an elbow 54. The elbow 54 is connected to a coupler pipe 55 and a suitable flexible tubing 56 is connected to the coupler pipe 55 for attachment to a fluid circulating system. A socket 57, having a slot 58 in one side thereof, is secured to the nipple 52 and is adapted to receive one of the tubular extensions 26 or 28 of the casing of the cooling jacket. The extension 26 or 28 is secured to the socket 57 by a longitudinally slotted clamping member 75.

59 which is provided with interior flanges 60 and 61. The flange 60 fits into slot 62 in the extension 26 or 28, while the flange 61 fits between the circumferential flanges 47 on the 5 coupler 46. The socket 57 may be forced against the adjacent end of the extension 26 or 28 by rotating the coupler member 46 to form a fluid-tight connection.

When it is desired to remove the device from 10 the support, the couplers 46 are rotated to withdraw the sockets 57 from the extensions 26 and 28. The clamping members 59 are then removed so that the extensions 26 may be withdrawn through the slots 58 of the sockets, the 15 device rocking about the upper sockets, with the inlet extensions 28 serving as bearings or trunnions. The device may then be completely detached from the support by withdrawing the extensions 26 from the associated sockets. In 20 mounting the device upon the support, the reverse procedure is, of course, followed.

Although the invention has been described with particular reference to high power electron 25 discharge devices, it may be used to advantage in other assemblies of similar character where it is desired to cool a device efficiently and effectively. Moreover, modifications may be made in the specific construction shown and described without departing from the scope and spirit of the 30 appended claims. For example, three or more outlets and inlets may be used instead of two, the outlets and inlets being so disposed that the pressures occasioned by the streams flowing therethrough are neutralized to prevent swirling 35 action of the cooling medium.

What is claimed is:

1. An electron discharge device comprising an 40 enclosing vessel including a cylindrical metallic portion adapted to serve as the anode of the device, an electron emission electrode within said vessel cooperatively disposed with respect to said anode, a casing including a cylindrical shell encircling said anode and closely spaced with respect thereto to form a narrow tubular passageway, said casing having a toroidal end portion forming an enlarged chamber at one end of said shell, means defining a restricted opening between said chamber and said tubular passageway, a plurality of inlets connected to said toroidal end portion and disposed at such angles to 50 one another that the resultant pressure of the cooling streams flowing through said inlets in one plane is substantially zero, and an outlet connected to said shell remote from said end portion.

2. A cooling jacket for an electron discharge device of the external anode type, comprising a shell adapted to be disposed about the anode of the device to form a narrow passageway therewith, an inlet chamber at one end of said shell, a pair of diametrically opposed inlet extensions for said chamber, and an outlet extension communicating with said passageway remote from said chamber.

3. A cooling jacket for an electron discharge device of the cylindrical external anode type, comprising a cylindrical shell adapted to be concentrically disposed about the anode of the device to form a narrow tubular passageway therewith, an inlet chamber at one end of said shell of greater cross-sectional area than the cross-sectional area of said passageway, means defining a restricted annular channel between said chamber and said passageway, a pair of diametrically

opposed inlet extensions for said chamber, and an outlet extension communicating with said passageway remote from said chamber.

4. A cooling jacket for an electron discharge device of the cylindrical external anode type, comprising a cylindrical shell adapted to be concentrically disposed about the anode of the device to form a narrow annular passageway therewith, means defining a chamber of greater cross-sectional area than said passageway at 10 each end of said shell, means defining a restricted channel between said passageway and said chambers, a pair of diametrically opposed inlet extensions communicating with one of said chambers, and an outlet extension communicating with the other of said chambers. 15

5. In combination, an electrical device having a cylindrical metallic portion adapted to be cooled, and a casing comprising a cylindrical shell concentrically disposed about said portion 20 and closely spaced with respect thereto to form a tubular passageway having a hollow toroidal member at each end of said casing secured to said metallic portion, the inner inside walls of each of said toroidal members being spaced 25 apart to provide a restricted annular channel between each of said toroidal members and said passageway, a pair of radially extending diametrically opposed tubulations forming inlets to one of said toroidal members, and a pair of radially extending diametrically opposed tubulations forming outlets from the other of said toroidal members. 30

6. An electron discharge device comprising an enclosing vessel having a cylindrical metallic 35 portion forming the anode of the device, a cathode within said vessel, a casing including a cylindrical shell concentrically disposed about said anode and forming a narrow tubular passageway therewith, a hollow toroidal member at 40 each end of said shell and integral therewith, said toroidal members being secured to said anode and defining expansible joints between said anode and said shell, means defining a restricted channel between each of said members 45 and said passageway, an inlet extending from one of said toroidal members, and an outlet extending from the other of said members.

7. In combination, an electron discharge device comprising an enclosing vessel having a 50 cylindrical metallic portion adapted to serve as an anode of the device, an electrode within said vessel cooperatively disposed with respect to said anode, a casing mounted upon said metallic portion and forming a cooling jacket therewith, 55 said casing including a shell disposed about said metallic portion and closely spaced with respect thereto to form a narrow tubular passageway, hollow toroidal members integral with said shell at the ends thereof encircling said vessel and forming chambers of greater cross-sectional area than said tubular passageway, means defining a restricted annular opening between each of said chambers and said passageway, a pair of radially extending diametrically disposed 60 tubulations on each of said toroidal members forming inlets and outlets respectively for said jacket, a support including coupler members forming sockets for said tubulations, and means for connecting said coupler members with a 65 fluid circulating system. 70
